W. E. STEWART

FOUNTAIN PEN

Filed Dec. 14, 1926

INVENTOR.
William E. Stewart
BY
J. Granville Meyers
ATTORNEY

UNITED STATES PATENT OFFICE.

WILLIAM E. STEWART, OF NASHVILLE, TENNESSEE.

FOUNTAIN PEN.

Application filed December 14, 1926. Serial No. 154,709.

The general object of the invention is to provide a fountain pen having new and improved filling mechanism and especially a new, simple and advantageous arrangement 5 of ink chambers, filling and pen feeding passages, filling tube, valves and valve controlling means co-operating with a tubular filling plunger or piston.

An additional object is to provide a new 10 and improved snap or spring cap fastener.

The characteristics and advantages of the invention are further sufficiently explained in connection with the following detail description of the accompanying drawing, 15 which shows one representative embodiment of the invention. After considering this example, skilled persons will understand that many variations may be made, and I contemplate the employment of any structures 20 that are properly within the scope of the appended claims.

Fig. 1 is a longitudinal section of a structure embodying the invention in one form.

Fig. 2 is a section at 2—2, Fig. 1.

Fig. 3 is a partial section showing the parts in different operative position from that of Fig. 1.

The tubular body 1 has at the upper end an extension 2 of reduced diameter externally threaded and at the inner end of this extension the main cylindrical bore 3 of the body terminates at a shoulder 4. The outer surface of the body near its lower end is tapered, as at 5 and this end of the body 30 has an internal screw thread 6. Secured in the lower end of the body by connection with this screw thread is a structure which may vary greatly in detail, that is to say, it may be made in one or more parts and 35 the form of the parts may vary, the example given being an approved structure which is preferred in some cases, largely because of manufacturing economy and convenience of assembly. A tubular connector 7 is 40 threaded externally at its inward end to engage the internal thread 6 of the body, and is provided with a stop shoulder 8 to engage the end of the body. Outwardly from the shoulder the connector has a portion 9 45 of somewhat reduced diameter, internally screw threaded. A sleeve 10, which for convenience may be called the pen holder, has a reduced inward extension 11 threaded to engage in the internal screw thread of the 50 connector. At the base of the threaded portion is a shoulder 12 to engage the end of

the connector. A feeder body 13 is inserted and secured by a tight fit or otherwise in the tubular pen holder. The inner end of the feeder body is arranged with relation 60 to the pen holder extension 11, so as to provide therein a chamber 14 which communicates with the larger chamber 15 within the inward end of the connector, these chambers directly connecting and providing ink 65 spaces, and also accommodating the valves and valve spring referred to later.

The pen point 15^a is inserted and secured as usual between the feeder body and the pen holder, and the feeder body is provided 70 with a feed channel 16 leading to ink chamber 14. The feeder body is centrally bored from its inward end to provide a filling duct or channel 17, this terminating at 18. From the under side of the feeder body a filling 75 hole 19 is drilled communicating with the filling channel.

A filling tube 20 is located centrally within the body, its lower end extending substantially within the filling channel 17. On this tube is a conical valve 21 co-operating with the inner end of the filling channel as a seat. Also on the tube is a disc valve 22 co-operating with a seat disc 23 inserted with a tight or press fit in a shallow counterbore 24 in the inner end of the connector. In this valve seat disc is a central hole 25 dimensioned to provide substantial clearance about the filling tube or an enlargement 26 thereon, which may be provided as a part 80 of the disc valve 22. A helical spring 27 is located about the filling tube and compressed between the inner end of the filler body and the disc valve 22 and when unrestrained, moves the tube upward and thereby places the valve 22 in closed position and valve 21 in open position. A tubular piston or filling plunger 30 extends through the major part of the barrel or body 1 above the pen holder and valve structure. 85 This includes an upper portion 31, diameter for a close sliding fit in the barrel extension 2 and a lower portion 32 dimensioned for a close sliding fit in the main bore 3 of the barrel. These portions are defined by a shoulder 33 and a packing washer 34 is located against this shoulder. The upper plunger portion terminates in a head 35 annularly channeled to provide a finger grip 36. A compressible packing or washer 37 is located against the inner face of the head to co-operate with the upper end of 90

the filling tube. The upper end of the barrel is closed and the head of the plunger is housed by an upper cap 38 internally threaded to engage the thread on the barrel extension 2. This top cap tightly seals the upper end of the barrel and prevents any possible leakage at this point, and also has an active function in co-operation with the plunger head and filling tube to definitely move the valves to one position or retain them therein.

The pen and adjacent parts are enclosed by the main or bottom cap 40, as usual, but a novel and improved quick acting or snap fastener is provided for the cap, to avoid the loss of time involved in the ordinary operation of screwing and unscrewing this cap. For this purpose a ring 41 is inserted in the inward portion of the cap against a shoulder 42 therein. The ring has an internal channel 43 and in this channel is located a split spring ring 44 of generally oval or ovate form, as shown in Fig. 2. The outer portion or extension 9 of the connector 7 is provided at a short distance from its outer end with an annular channel 45, and the outer end of the extension is slightly rounded or tapered, as at 46. When the cap is moved inward to closed position the spring ring 44 opens slightly as it passes over the outward end of the connector, this spring action being facilitated by the tapered or rounded end formation thereof, and then when the spring comes to the plane of the annular channel 45 it snaps into the channel and retains the cap firmly in position with the inner face of ring 41 resting against the connector flange 8. Although the cap is securely held, it may be quickly and easily removed by a straight outward pull without waste of time for screwing action, and is easily replaced. The inward portion of the main cap is also internally dimensioned to have a friction fit on the upper cap 38 for the convenient location of the main cap while writing, as usual.

Fig. 1 shows the parts in position for writing after removal of the main or bottom cap 40. The inner face of the top or head 35 of the top cap 38 engages the upper end of the head 35 of the filling plunger, and compressible washer 37 located against the inner face of the plunger head engages the upper end of the filling tube and holds the conical valve 21 with yieldable pressure on its seat, thus closing the filling passage 17 at its inner end. Spring 27 is compressed and disc valve 22 is maintained in open position, so that ink may flow from the main ink chamber, which is the hollow interior of the filling plunger, through the clearance space 25 to the ink chambers 15 and 14 and so through the feed channel 16 to the pen. When it is necessary to fill the pen, the pen end of the structure is immersed in ink sufficiently to

bring the filling hole 19 below the ink surface. After the top cap 38 is removed the plunger is pulled out by grasping its head or knob 36. As soon as the top cap is removed spring 27 moves the valve and filling tube upwardly, closing connection between ink chamber 15 and the interior of the plunger by engagement of valve 22 with its seat, and establishing communication between the filling channel 17 and chamber 14 by movement of valve 21 from its seat. As the plunger is pulled out therefore, ink is drawn in through hole 19, channel 17 and through the filling tube, emerging at the upper end of the tube and flowing back into the main reservoir, that is, the interior of the hollow filling plunger. When the plunger is returned to normal position any trapped air is forced out through the filling tube, channel 17 and hole 19. Finally the top cap 38 is screwed back in normal position and when it is fully seated, the filling tube and valves are repositioned, as shown in Fig. 1, ready for writing, in a manner which is obvious from preceding explanation.

I claim:

1. A fountain pen comprising a lower structure including means for holding a pen point, said lower structure having therein a feed channel and a filling channel, a filling tube, a tubular filling plunger, and means including valves co-operating with the filling plunger and tube to close the feed channel and establish connection through the filling channel and tube with the ink reservoir within the filling plunger and in another position of the plunger to close the filling channel and establish connection between the reservoir and the feed channel.

2. A fountain pen comprising a barrel, a tubular filling plunger, a lower structure including means for holding a pen point and providing an ink chamber, the lower structure also including distinct feed and filling channels communicating with the chamber, a partition also arranged as a valve seat between the ink chamber and the reservoir provided by the barrel and interior of the plunger, a reciprocable filling tube communicating with the filling channel, a valve on the tube adapted to close the filling channel and a valve on the tube adapted to operate with the partition which acts as a valve seat to close communication between the ink chamber and reservoir.

3. A fountain pen comprising a barrel, a tubular filling plunger, a lower structure including means for holding a pen point and providing an ink chamber, the lower structure also including distinct feed and filling channels communicating with the chamber, a partition also arranged as a valve seat between the ink chamber and the reservoir provided by the barrel and interior of the

plunger, a reciprocable filling tube communicating with the filling channel, a valve on the tube adapted to close the filling channel, a valve on the tube adapted to co-operate with the partition which acts as a valve seat to close communication between the ink chamber and reservoir, and a spring urging the filling tube and valves in one direction.

4. A fountain pen comprising a barrel, a tubular filling plunger, a lower structure including means for holding a pen point and providing an ink chamber, the lower structure also including distinct feed and filling channels communicating with the chamber, a partition also arranged as a valve seat between the ink chamber and the reservoir provided by the barrel and interior of the plunger, a reciprocable filling tube communicating with the filling channel, a valve on the tube adapted to close the filling channel, a valve on the partition which acts as a valve seat to close communication between the ink chamber and reservoir, and a spring action on the filling tube and valves and tending to move the first named valve to open position and the last named valve to closed position.

5. A fountain pen comprising a barrel, a tubular filling plunger, a lower structure including means for holding a pen point and providing an ink chamber, the lower structure also including distinct feed and filling channels communicating with the chamber, a partition also arranged as a valve seat between the ink chamber and the reservoir provided by the barrel and interior of the plunger, a reciprocable filling tube communicating with the filling channel, a valve on the tube adapted to close the filling channel, a valve on the tube adapted to co-operate with the partition which acts as a valve seat to close communication between the ink chamber and reservoir, the filling plunger having a head, and a compressible member therein co-operating with the adjacent end of the filling tube to move the tube and operate the valves.

6. A fountain pen comprising a barrel, a connector detachably inserted in one end thereof, a pen holder extending from the connector, a feeder body co-operating with the pen holder to retain a pen point and having a feed channel leading to the pen point, inward portions of the pen holder and connector providing an ink chamber, a disc at the inward end of said chamber having a central

aperture, the feeder body having a central bore leading to the ink chamber and a filling hole communicating with said bore, a filling tube having one end reciprocably located in said bore, a valve on the tube in the ink chamber to co-operate with the inner end of the feeder body and close the filling bore therein, another valve on the filling tube to co-operate with said partition and close the aperture therein through which the filling tube passes, a spring normally acting on the tube and valves to move them to one position, and a tubular filling plunger in the barrel having a head at its outer end and a compressible washer within the head arranged and positioned to co-operate with the upper end of the filling tube to move and hold the valves in another position.

7. A fountain pen comprising a barrel, a connector detachably inserted in one end thereof, a pen holder extending from the connector, a feeder body co-operating with the pen holder to retain a pen point and having a feed channel leading to the pen point, inward portions of the pen holder and connector providing an ink chamber, a disc at the inward end of said chamber having a central aperture, the feeder body having a central bore leading to the ink chamber and a filling hole communicating with said bore, a filling tube having one end reciprocably located in said bore, a valve on the tube in the ink chamber to co-operate with the inner end of the feeder body and close the filling bore therein, another valve on the filling tube to co-operate with said partition and close the aperture therein through which the filling tube passes, a spring normally acting on the tube and valves to move them to one position, a tubular filling plunger in the barrel having a head at its outer end and a compressible washer within the head arranged and positioned to co-operate with the upper end of the filling tube to move and hold the valves in another position, and an upper cap detachably connected to the upper end of the barrel and dimensioned to co-operate with the head of the filling plunger to retain it and the filling tube and valves in the last named or writing position.

Signed at Nashville in the county of Davidson and State of Tennessee this ninth (9th) day of December, A. D. 1926.

WILLIAM E. STEWART.
